Inventor.

Henry W. Eastman.

United States Patent Office.

HENRY W. EASTMAN, OF BALTIMORE, MARYLAND.

Letters Patent No. 77,263, dated April 28, 1868.

IMPROVED TOILET-ATTACHMENT FOR BUREAUS.

The Schedule referred to in these Letters Patent and making part of the same.

TO ALL WHOM IT MAY CONCERN:

Be it known that I, HENRY W. EASTMAN, of the city and county of Baltimore, State of Maryland, have invented a new and improved "Toilet-Attachment for Bureaus;" and do hereby declare that the following is a full, clear, and exact description of the construction and operation of the same, reference being had to the annexed drawing, (making a part of this specification,) in which my invention is represented by a perspective view.

This invention is a neat and ornamental attachment for bureaus, which serves the purpose of a support for holding and adjusting the mirror, while it furnishes a convenient receptacle for combs, brushes, perfumery, &c., &c.

In the drawing, A represents the bureau, and B a neat upright cabinet, resting on the top of the bureau, supported on its flanks by brackets, *b b*, properly ornamented with mouldings, *c c*, and provided with shelves, *s s*.

D is a hinged frame, which opens and closes upon the front side of the cabinet, like a door, and has a lock, *l*, by which it can be securely fastened when shut.

M is a mirror, hinged at its bottom to the bottom of the frame, as shown at *m m*, so as to open outward at the top, in the manner represented in the drawing, and closing into the frame D, when shut, so as to form, with the frame, a door to the cabinet.

At its top it is provided with an adjusting-rod, *r*, by which it can be fixed at any required inclination to the frame, and, as the latter turns on its side hinges, can assume a variety of angles with the front of the bureau, so as to accommodate itself to the position of the person using it. A drawer, G, may be provided under the door, in the cabinet.

The cabinet forms a convenient receptacle for the various articles of the toilet.

The whole device is a neat and ornamental appurtenance, which can be applied to any bureau.

Having thus described my invention, what I claim as new, and desire to secure by Letters Patent, is—

The toilet-attachment for bureaus above described, consisting substantially of the upright cabinet B, provided with horizontal shelves *s*, the frame D swinging on side hinges, and the mirror M, hinged to the frame D, and provided with an adjusting-rod or cord, *r*, the whole operating together in the manner and for the purposes specified.

HENRY W. EASTMAN.
